UNITED STATES PATENT OFFICE.

THOMAS M. DUDGEON, OF AVALON, PENNSYLVANIA.

DESIGN FOR A FIREPLACE-FRAME.

• 40,437.

Specification for Design.

Patented Jan. 11, 1910.

Application filed November 11, 1909. Serial No. 527,579. Term of patent 14 years.

To all whom it may concern:

Be it known that I, THOMAS M. DUDGEON, a citizen of the United States, residing at Avalon, in the county of Allegheny and State of Pennsylvania, have invented a new, original, and ornamental Design for Fireplace-Frames, of which the following is a specification, reference being had to the accompanying drawing, forming part thereof.

The figure is a front elevation of the frame, showing my new design.

I claim:

The ornamental design for a fire place frame, as shown.

THOMAS M. DUDGEON.
